UNITED STATES PATENT OFFICE

FRED A. SCHMITZ, OF CANTON, OHIO, ASSIGNOR OF FORTY-NINE TWO-HUNDREDTHS
TO CLARENCE W. AUSTIN AND FORTY-NINE TWO-HUNDREDTHS TO WILLIAM ISLER,
BOTH OF CANTON, OHIO

DESIGN FOR A GOLF PUTTING GREEN

Application filed September 16, 1929. Serial No. 32,775. Term of patent 7 years.

To all whom it may concern:

Be it known that I, FRED A. SCHMITZ, a citizen of the United States, residing at Canton, in the county of Stark and State of Ohio, have invented a new, original, and ornamental Design for a Golf Putting Green, of which the following is a specification, reference being had to the accompanying drawing, forming a part hereof.

I claim:

The ornamental design for a golf putting green, substantially as shown.

In testimony whereof I affix my signature.

FRED A. SCHMITZ.
